UNITED STATES PATENT OFFICE.

BURDETTE S. BAYLE, OF AMBRIDGE, PENNSYLVANIA.

PAPER-HOLDER.

Specification of Letters Patent.

Patented Oct. 19, 1915.

1,157,286.

Application filed October 14, 1914. Serial No. 866,659.

To all whom it may concern:

Be it known that I, BURDETTE S. BAYLE, a citizen of the United States, residing at Ambridge, in the county of Beaver and State of Pennsylvania, have invented certain new and useful Improvements in Paper-Holders; and I do hereby declare the following to be a full, clear, and exact description of the invention, such as will enable others skilled in the art to which it applies to make and use the same.

This invention relates to holders for holding and dispensing rolls of paper, such as toilet paper and towels; and it consists in the novel construction and combination of the parts hereinafter fully described and claimed.

In the drawings, Figure 1 is a front view of a paper holder constructed according to this invention. Fig. 2 is a detail view of the roller spindle. Fig. 3 and Fig. 4 are cross-sections, taken on the lines A—A and B—B respectively in Fig. 1.

The holder is provided with a stationary support or base plate *a* from which project two similar brackets *b*. These brackets may be formed integral with the base plate, if desired, or they may be secured to it. Each bracket is provided with an upwardly and forwardly projecting slot *g*, and *f* is a metallic spindle having cylindrical bearings at its ends which are mounted to roll and slide in the slots *g*.

The roll shaft *c* is preferably rectangular in cross-section, and it is forced into the roll of paper *F*, which is indicated by the dotted lines in Fig. 4. Toothed pinions *d* are formed on or secured to the end portions of the shaft *c*. Toothed racks *e* are secured to the brackets *b* on the lower sides of the slots *g*, and these racks are arranged in gear with the pinions *f*. The spindle *f* is slideable in a hole in the shaft *c*, and it has a circumferential groove *i* formed in it. This shaft *c* has a notch *j* formed opposite the groove *i*, and *h* is a spring catch secured at one end to the shaft and arranged in the notch *j*. The other end of the spring catch projects from the notch, so that the spring can be retracted when there is no paper on the shaft

and when the usual paste-board center tube has been removed. The spindle is released by retracting the spring catch, and the spindle can then be slid longitudinally out of the shaft, so that it and the shaft can be removed from the brackets, to permit a new roll of paper to be placed on the shaft.

In Fig. 4 the roll is shown nearly used up. When new, the roll bears against the base plate *a*, and the spindle *f* is in the middle part of the slots *g*. In use, the free end portion of the paper is pulled upon by hand, so that the shaft is revolved. The toothed pinions run up the racks until the spindle strikes the upper ends of the slots *g*. The paper is then torn off, the paper of the roll being preferably perforated at suitable intervals. The roll runs back by gravity whenever a sheet is torn from it. As the roll decreases in size, it rolls back farther, so that its increased forward and rotary motion compensates for its decreased size, and sheets of the same length are always torn from the roll, the device adapting itself automatically to the varying size of the roll. The locking catch is covered by the roll, so that it cannot be retracted until the whole of the paper has been used.

What I claim is:

In a paper holder, the combination, with a rectangular roll shaft for engaging the roll of paper, said shaft having a hole at its axis, and having a notch in one of its sides, arranged at its middle part and communicating with the said hole, a spindle slideable in the said hole and having a circumferential groove which registers with the said notch, a spring arranged in the notch and secured to one side of the rectangular shaft with its free end projecting beyond its opposite side and with its middle part engaging with the said groove, and means for supporting the said spindle and shaft.

In testimony whereof I have affixed my signature in the presence of two witnesses.

BURDETTE S. BAYLE.

Witnesses:

J. F. SNYDER,
C. ROY KERR.
